SEWING MACHINE

Eugene C. Zablocki, Detroit, Mich., assignor to
 Briggs Manufacturing Company, Detroit, Mich.,
 a corporation of Michigan

Application March 23, 1936, Serial No. 70,345

5 Claims. (Cl. 112—245)

This invention relates to a mechanism and method particularly adapted for forming lines of stitching in trim panels for vehicle bodies or the like, and has for an object, broadly, the provision of simple means and a method for stitching padded trim panels and for tightening each stitch after it is completed.

The present fashion in interior trim for automobiles calls for trim panels of relatively stiff fiber board or the like covered with flat padding and fabric upholstery material and with several vertical lines of stitching forming deep vertical creases in the upholstered surface, the stitches being hidden in the bottoms of the creases. If an attempt is made to produce such panels with the sewing machines that are at present on the market, it is found that the stitches are not formed tightly enough to compress the padding under them to any appreciable extent. The result is that the stitching creates only a shallow groove in the upholstered surface and the thread is clearly visible. The object of this invention is specifically the provision of a sewing machine which will pull each stitch very tight after it is completed so that, when it is used for stitching upholstered trim panels, the upholstery fabric will be pulled down into the padding along the line of stitches into a deep crease.

Another object of this invention is to provide a means for tightening stitches that can be readily adjusted and that involves no bearings not otherwise required by the machine.

Another object of this invention is to provide a means for tightening stitches that can be readily attached to existing sewing machines.

Other objects of this invention will appear in the following description and appended claims, reference being had to the accompanying drawings forming a part of this specification wherein like reference characters designate corresponding parts in the several views.

Fig. 1 is a perspective view of the upper part of the stitching mechanism of a sewing machine embodying the present invention, showing the needle bar at the lowest point of its path and the tightening mechanism in operation.

Fig. 2 is a perspective view similar to Fig. 1 but showing the needle bar at the highest point in its path.

Fig. 3 is a sectional view through an upholstered trim panel stitched by the machine, taken on the line 3—3 of Fig. 1.

Fig. 4 is a partly diagrammatic view showing the stitch and the stitch forming mechanism just before a stitch is to be tightened, with many parts,

such as the bed of the machine, omitted to simplify the drawing.

Fig. 5 is a view similar to Fig. 4 showing a stitch being tightened.

Fig. 6 is a view similar to Fig. 4 showing the completion of the stitch tightening operation.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

While the invention is susceptible of application to many types of sewing machines and may be formed as an integral part thereof, its present commercial form consists of an attachment applied to the standard type of double chain stitch machine known as the "Phales Maniplex".

This machine (of which only a portion is shown in the drawings) consists of a flat horizontal bed along which the material or work 10 to be stitched is moved at the proper speed by conveyor chains travelling in grooves in the bed and having upward projections adapted to engage the work. The work illustrated comprises a stiff, cardboard-like material 10a forming the backing of a trim panel, a layer of fibrous padding 10b, and a sheet of upholstery fabric 10c lying one on top of the other.

The stitching mechanism comprises a portion above the bed which carries the needles 11 and a portion below the bed which carries the loopers 12 which cooperate with the needles to form the stitches. The needle carrying and actuating mechanism is carried by a bridge 13 extending across above the bed of the machine and comprises a plurality of units, only one of which is shown in the drawings since they are all alike. Each of these units comprises a mounting block 14 secured to the bridge 13 and extending down toward the bed of the machine. The lower end of the mounting block is curved forward and forked to form a pair of aligned horizontal bearings 14a which carry the pivot 15a of an upwardly extending needle bar guide 15.

A needle bar 16 is vertically slidable in the needle bar guide 15 and extends up to the mechanism which actuates it. This mechanism moves the upper end of the needle bar 16 in a path which

extends back, down, forward and up, so that the needle bar 16 is simultaneously reciprocated up and down and rocked back and forth about the pivot of the guide block and the needles 11 on the lower end of the needle bar are successively moved forward, down, back and up. These movements and the movement of the work 10 across the bed of the machine are so synchronized and related that the needles 11 are moving backwards with and at the same speed as the work 10 during the part of each stitch forming cycle in which they extend down into the work 10.

The needles 11 extend into material through slots 17 in a presser foot 18 carried at the lower end of a presser foot bar 19 which is slidably mounted in guides on the mounting block 14. The presser foot 18 is urged down against the material being stitched by springs 20 and 21 acting on the presser foot bar and has ribs 18a on its lower face in line with the needles 11 to press down the padding 10b along the lines to be stitched.

The portion of the stitch forming mechanism under the bed of the machine comprises the loopers 12, one for each needle 11, and the mechanism to actuate them. This portion of the machine is not affected by the present invention and therefore only the working end of the looper 12 is shown or described herein.

The present invention consists of a means for tightening the thread 22 leading to the needle at just the instant that the needle 11 reaches its lowermost position and is pulling tight the stitch previously formed. The particular embodiment of the invention shown in the drawings comprises a thread tightener 23 adjustably bolted to the needle bar guide 15 and arranged to project up between two horizontally spaced thread guides 24 which are mounted on a U-shaped bracket 25 on the needle bar 16. These parts are arranged and adjusted so that the two thread guides 24 come down level with the top of the tightener 23 just before the needle bar 16 reaches the end of its downward stroke. Because of this arrangement, the needle thread 22, which leads from a spool 26 through a tensioner 27, thence through the two horizontally spaced guides 24 and down to the needle 11, comes into contact with the tightener 23 and is pulled up tight like a bowstring, just as the needle 11 reaches the bottom of its stroke. As shown in Figs. 4, 5 and 6, the tightening means 23 and 24 pulls the needle thread 22a along in the stitch being formed and tightens the thread 22b in the stitch behind it, compressing the padding 10b under the thread 22b in that stitch so that the thread 22b lies well below the level of the fabric 10c resting on top of the padding 10b at each side of the line of stitching. Once the stitch is pulled down tight in this way, it is held there by the loop 22c at its end projecting through the work 10 between it and the next stitch 22a and engaged by one loop 28a and engaging the next loop 28b of the looper thread 28. Thus, the line of stitching makes a decorative depressed line in the surface of the upholstered panel and more securely holds the

fabric 10c to the backing member 10a than if the padding 10b were uncompressed and the stitches rested on the surface of the material.

I claim:

1. In a sewing machine having a needle bar adapted to be reciprocated endwise, thread tensioning means and a needle carried by the needle bar, a U-shaped bracket carried by said bar, a pair of spaced thread guides mounted on said bracket in a plane substantially perpendicular to the needle bar, and a relatively stationary thread tightening member placed so that the two thread guides move slightly past and at either side of the thread tightening member as the needle bar approaches the end of its stroke towards the work. 5

2. In a sewing machine having a guide, a needle bar adapted to be reciprocated endwise in the guide, thread tensioning means and a needle carried by the needle bar, the improvement which 20 consists of a pair of thread guides secured to the needle bar and spaced apart in a substantially horizontal plane in front of and at an angle to the needle bar, and a thread tightening member fixed with respect to the guide and projecting 25 away from the work to a point past a line joining the two spaced thread guides when the needle bar is at its position closest to the work.

3. In a sewing machine having a frame, a guide, a pivot connecting the guide to the frame, 30 a needle bar slidably mounted in the guide and adapted to be simultaneously reciprocated endwise and rocked with the guide about the pivot, and a thread tensioning means and a needle carried by the needle bar, the improvement which 35 consists of a pair of thread guides carried by the needle bar and spaced apart in a plane at an angle to the needle bar and a thread tightening member fixed with respect to the guide and projecting away from the work to a point reached by a 40 thread extending between the guides as the needle bar approaches the end of its stroke towards the work.

4. In a sewing machine having a needle bar adapted to be reciprocated endwise, a guide for 45 said needle bar, thread tensioning means and a needle carried by the needle bar, a thread guiding bracket also carried by said bar, and an adjustable thread tightener located below and cooperable with said bracket and carried by said 50 guide for tightening up the thread between the tensioning means and the needle as the needle bar approaches the end of its stroke towards the work.

5. In a sewing machine having a needle bar 55 adapted to be reciprocated endwise, a guide for said needle bar, thread tensioning means and a needle carried by the needle bar, a bracket also carried by said bar, spaced thread guides carried by the bracket, and means located below said 60 bracket and engageable with the thread between said thread guides for tightening the thread as the needle bar approaches the end of its stroke towards the work.

EUGENE C. ZABLOCKI.
